[57] **CLAIM**

The ornamental design for the self-watering plant container,
as shown and described.

DESCRIPTION

FIG. 1 is a front elevational view of the self-watering plant container showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is an exploded assembly view thereof in elevation;
and,
FIG. 8 is a bottom view of the interior elements on an enlarged scale thereof.
